UNITED STATES PATENT OFFICE.

WALTER J. CONLON, OF CHICAGO, ILLINOIS.

CLOTHES-WRINGER.

1,375,130.

Specification of Letters Patent. Patented Apr. 19, 1921.

Application filed March 25, 1915. Serial No. 16,860.

To all whom it may concern:

Be it known that I, WALTER J. CONLON, a citizen of the United States, residing at Chicago, in the county of Cook and State 5 of Illinois, have invented a certain new and useful Improvement in Clothes-Wringers, of which the following is a full, clear, concise, and exact description, reference being had to the accompanying drawings, forming 10 a part of this specification.

My invention relates to clothes wringers and is concerned with an attachment therefor in the nature of a guard for preventing the catching of one's fingers in between the 15 wringer rolls. This guard attachment is so constructed as not to interfere in any way with the wringing of clothes and is also so formed that it may readily be moved from one side of the wringer to the other so as 20 to provide for passing the clothes therethrough in either direction.

My invention is illustrated in the accompanying drawing in which,

Figure 1 is a front elevational view of a 25 wringer having my attachment applied thereto.

Fig. 2 is a side elevational view thereof.

Fig. 3 is a cross-sectional view taken on the plane of the line 3, 3, of Fig. 1, and 30 looking in the direction indicated by the arrows, and

Fig. 4 is an isometric view showing the attaching mechanism.

My invention is not concerned with the 35 precise construction of the wringer so a very general description thereof will suffice. The frame-work 5 is composed of the upright members 6, 6, and the cross piece 7, securely fastened together, the upright 40 members being adapted for attachment to a tub or the container of a washing machine. The upright members 6, 6, are slotted, as illustrated at 8 in Fig. 2, and the bearings 9, 9, for the roller shafts 10, 10, are mounted 45 in these slots. This arrangement permits of the vertical adjustment of the rollers and springs 11, 11, are provided to hold the rollers together. These springs may be adjusted in their tension by means of the 50 adjusting screws 12, 12, and a releasing mechanism 13, with the details of which we need not here be concerned, may also be provided. Each of the shafts 10, 10, carries the roller 14 and upon each roller the usual rubber 55 covering 15 is provided. The shaft of the

lower roller is extended beyond the sides of the corresponding uprights 6 and is provided with the squared end 16 to which either a handle or an electric motor may be applied. Secured to the inner face of each 60 of the uprights 6 beneath the rollers, is a drip spout 17 which conducts any water dripping from the ends of the rollers into the rocking water shed 18, this water shed being mounted upon a pivot 19 so that it 65 may be thrown either way to direct the dripping water in the direction desired.

Upon the front and back faces of each of the uprights 6, sockets 20, 20, are provided, these sockets forming the supporting means 70 for the attachment, which I shall now describe. The sockets 20 are illustrated in detail in Fig. 4.

The attachment is in the form of two guiding boards which form a hopper shaped 75 structure which, when mounted in place, leads to the contact surfaces of the rollers. The lower board 21 is mounted at each end in a frame piece 22, constructed at the bottom with a U-shaped channel 23 to receive 80 the board. Upon the outside of each of these frame pieces a bracket 24 is provided, the bracket being L-shaped and having its leg in the form of a key 25. This key is adapted to fit in the socket 20, as is clearly 85 evident from Fig. 4. With the two brackets properly supported in their respective sockets, the board 21 will slope upwardly to a point close to the rolls and at the contacting surfaces thereof, which arrangement 90 is clearly shown in Fig. 3. Each of the supporting members 22 is provided with an upwardly extending part 26, at the upper end of which a channel shaped supporting member 27 is pivoted at 28. The two channel shaped supporting members 27 support the top board 29, which slopes downwardly 95 toward the rolls, as illustrated in Fig. 3.

Extending upwardly from each of the brackets 24 is a rod 30 upon which a collar 100 31 is held by means of a set-screw 32. A bracket 33 is secured to the corresponding member 27 by means of rivets 34 and the arm 35 of this bracket is bifurcated, as illustrated in Fig. 4, so that the rods 30 may pass 105 through the tangs thereof. A spring 36, of helical form, rests upon a washer 37, which in turn rests upon the bracket 33, it being understood that the bracket 33 passes around the rod 30 above the collar 31. Above the 110

spring 36 another washer 38 is provided and above this collar 39 is held by means of a set-screw 40. It will now be seen that under normal conditions the board 29 is maintained in its lowermost position by reason of the engagement of the bracket 33 with the collar 31 which may be adjusted to the proper point. The collar 39 being properly adjusted so as to store the desired amount of power in the spring 36, it will be seen that this downward force is primarily exerted to hold the board 29 in its initial position, and that if the board 29 is raised it is raised against the tension of this spring. 15 When the parts are in their normal position, as shown in Fig. 3, the space between the inner end of the top board and the inner end of the bottom board is such that it is impossible to pass one's finger therethrough. It 20 is sufficient, however, to feed clothes therethrough and to the engaging rolls. Once the clothes are caught by the rolls, which can be carried out by feeding just so much of a garment, for instance, as will not require 25 the raising of the top board, the application of one's finger is no longer necessary. However, the pull of the operating rolls is sufficient to draw the garment through the wringer and if parts of the garment are 30 thicker than can pass through the normal space between the two boards, the top board will rise against the tension of the springs 36 so as to accommodate the passage of the garment. The tension of the springs 36, 36, 35 is so adjusted as to make it impossible to raise the top board by merely pushing one's finger or fingers into the space between the two boards. In this way it is impossible to have the fingers reach the contacting and 40 engaging surfaces of the rolls. This tension, of course, is easily overcome by clothes being drawn through the guards by the action of the rolls, so that the proper wringing of the clothes is not interfered with. 45 In feeding clothes to the wringer it is, of course, very simple to push a thin portion of a garment for instance through the space between the two boards and into the engaging zone between the two rolls. In this way 50 the clothes are grasped while the fingers are at a safe distance from the rollers.

It will be readily seen that the attachment can be moved from one side of the wringer to the other, which is particularly desirable 55 when the wringer is applied on a washing machine.

The supporting member 22 is preferably provided with the side flange 41 so as to guard the water running off.

60 I claim as new and desire to secure by Letters Patent:

1. In combination, a clothes wringer having a pair of coöperating rollers, and a hopper shaped guard leading to said rollers, 65 one wall of said hopper shaped guard being

movable independently of the movement of the rollers to vary the outlet of said hopper at said rollers.

2. In combination, a clothes wringer having a pair of coöperating rollers, and a hopper shaped guard leading to said rollers, 70 the feed opening of said guard at said rollers being normally limited in size but being enlargeable independently of the movement of the rollers, and spring means to 75 resist enlargement of the opening in the hopper.

3. In combination, a clothes wringer having a pair of coöperating rollers, and a hopper shaped guard leading to said rollers, 80 the feed opening of said guard at said rollers, being normally limited in size but being enlargeable independently of the movement of the rollers by the passage of clothes therethrough, said feed opening being above the lower side of the hopper. 85

4. In combination, a clothes wringer having a pair of coöperating rollers, and a hopper shaped guard leading to said rollers, the feed opening of said guard at said 90 rollers being normally limited in size but being enlargeable independently of the movement of the rollers.

5. In combination, a clothes wringer having a pair of coöperating rollers, and a 95 guard composed of two boards inclined toward each other and leading to said rollers, one of said boards being pivoted and held in normal position by spring tension.

6. In combination, a clothes wringer having a pair of coöperating rollers and a 100 guard composed of two boards inclined toward each other and leading to said rollers, one of said boards being rigidly secured to a frame, the other of said boards being piv- 105 otally mounted to said frame and held in normal position by spring tension.

7. In combination, a clothes wringer having a pair of coöperating rollers, a guard composed of two boards inclined toward 110 each other and leading to said rollers, one of said boards being mounted between two channel members, the other of said boards being mounted between two other channel members, the first mentioned two channel members being rigidly secured to brackets, 115 said brackets being adapted to fit into sockets mounted on either side of the frame of the wringer, rods secured to said brackets and provided with adjustable upper and lower collars, the second mentioned two channel members being pivotally secured to supports carried by said first mentioned channel members, brackets mounted on said second mentioned channel members, said 120 brackets being normally held down on the lower of said collars by a spring mounted on said rod and held under tension by the upper collar.

8. In combination, a clothes wringer hav- 130

ing a pair of coöperating rollers and a guard composed of two members inclined toward each other and leading to said rollers, one of said inclined members being 5 secured to a frame, said frame adapted to fit into sockets mounted on either side of the main frame of the wringer, the other of said inclined members being pivotally mounted to said first mentioned frame and 10 held in normal position by spring tension.

9. In combination, a clothes wringer having a pair of coöperating rollers and a hopper shaped guard leading to said rollers, one side of said guard being rigidly secured 15 to a frame, said frame adapted to engage sockets mounted on either side of the main frame of the wringer, the other side of said guard being pivotally secured to said first mentioned frame and held in normal position 20 under spring tension.

10. In combination, a clothes wringer having a pair of coöperating rollers and a hopper shaped guard leading to said rollers, one side of said guard being rigidly secured 25 to a frame, the other side of said guard being pivotally mounted to said frame, the feed opening of said guard at said rollers being normally limited in size but enlargable by the drawing of clothes therethrough 30 under the pull of the rollers.

11. In combination, a clothes wringer having a pair of coöperating rolls, a hopper shaped guard comprising an upper board or plate, a lower board or plate, said boards 35 or plates diverging upwardly and downwardly respectively from the bite of the rolls, said boards or plates being normally slightly separated and being yieldably mounted with respect to each other to 40 permit greater separation.

12. In combination, a frame, a pair of rolls on the frame, a guard composed of two boards or plates, one board or plate being inclined upwardly toward the bite 45 of the rolls and the other being inclined

downwardly toward the bite of the rolls, said boards or plates being mounted on said frame, one of said boards being yieldably mounted with respect to the other, said boards or plates having an opening between 50 them adjacent the bite of the rolls to permit of the introduction of the edge of an article into the bite of the rolls without permitting the fingers of the operator passing therethrough. 55

13. In combination, a frame, a pair of rolls in the frame, a guard in front of said rolls, said guard comprising a board or plate rigidly secured to the frame, and a second board or plate yieldably mounted at an 50 angle to the first board or plate to form a trough.

14. In combination, a frame, a pair of rolls on the frame, a guard in front of said rolls having an upwardly inclined lower 65 wall and an upper guard wall, the upper edge of the inner end of the lower wall being on substantially the level of the top line of the lower roll, and the upper board being yieldingly held toward the lower board to 70 permit the passage of articles to be operated upon.

15. In combination, a frame, a pair of rolls on the frame, a guard in front of said rolls having a fixed lower upwardly inclined wall ending on substantially the level of the top line of the lower roll, and spaced therefrom, and a yieldingly held downwardly inclined upper wall which, together with the lower wall, forms a roll guard having 75 a normally limited delivery opening space from said rolls. 80

In witness whereof, I hereunto subscribe my name this 17th day of March, A. D. 1915.

WALTER J. CONLON.
